UNITED STATES PATENT OFFICE.

MICHAEL F. BROGAN, OF LAWRENCE, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SEWING-MACHINE.

1,317,613.

Specification of Letters Patent. Patented Sept. 30, 1919.

Application filed August 12, 1915. Serial No. 45,218.

To all whom it may concern:

Be it known that I, MICHAEL F. BROGAN, a citizen of the United States, residing at Lawrence, in the county of Essex and State 5 of Massachusetts, have invented certain new and useful Improvements in Sewing-Machines; and I do hereby declare the following to be a full, clear, and exact description of the invention, such as will enable others 10 skilled in the art to which it appertains to make and use the same.

The present invention relates to an improvement in sewing machines, and more particularly to lock stitch wax thread sewing 15 machines.

Heretofore, the lock stitch sewing machine has employed a single awl and a single needle and other coöperating instrumentalities in the formation of the stitch, and, obviously, the limit of the rate of speed at which the machine can be operated is determined by the rate of speed at which the 20 stitches can be formed and set. Taking the outsole stitcher, for example, the speed at which it can be operated in sewing outseams is determined in a large measure by the rate at which the stitches can be formed and set in the materials, one stitch at a time. The principal object of the present 25 invention is to produce a lock stitch sewing machine in which two stitches are formed at each cycle of operations of the machine. According to this invention, if the speed of the machine be maintained the same as before, the rate of seam formation will be doubled, or if the speed of the machine be reduced, still the output of the machine will be materially increased, or if the speed of the machine be halved, for example, the 30 rate of seam formation will be maintained the same as before, thereby in the first example doubling the output, or in the second example materially increasing it, or in the third example maintaining the output the same.

In the latter two examples, the speed of the machine being materially decreased, the rate of wear of the machine is reduced, and the life of the machine is much increased. The machine of the present invention 35 contemplates other features of novelty, hereinafter referred to and particularly pointed out in the claims.

In the accompanying drawings illustrat-

ing the preferred form of the invention, Figure 1 is a top plan of the machine;

55

Fig. 2 is an end elevation with the counter removed, showing the bearing and main shaft in section;

Fig. 3 is a front elevation;

Fig. 4 is an enlarged top plan of the front 60 of the machine, with parts removed for clearness, showing certain of the stitch forming instrumentalities;

Fig. 5 is a left end elevation with the pulley removed and the main shaft shown 65 in section;

Fig. 6 is an enlarged left elevation of the tension wheel takeup, auxiliary takeup, thread measurer, and associated parts;

Fig. 7 is a right end elevation with the 70 fourth cam removed;

Fig. 8 is a top plan view of the machine, with the cam shaft and cams removed, the cam shaft bearing and certain other parts being shown in sectional plan;

75

Fig. 9 is a front sectional elevation of the shuttle and associated parts;

Fig. 10 is a horizontal section on line 10—10, Fig. 9, looking in the direction of the arrows;

80

Fig. 11 is a back view of the shuttle driver plate;

Fig. 12 is a side elevation of the shuttle;

Fig. 13 is a left side elevation of the fourth cam disk;

85

Fig. 14 is a left side elevation of the second cam disk;

Fig. 15 is a development of the peripheral face of the first cam disk;

Figs. 16, 17 and 18 are similar developments of the second, third and fourth cam disk faces respectively;

90

Fig. 19 is an enlarged front elevation of a portion of the machine shown with the work in position, with the needles looped 95 ready to draw bights of the under or needle thread up through the material;

Fig. 20 is a similar view after the needles have risen and drawn bights of thread up through the material, and while the spreader 100 holds the loops thus drawn up open, ready to receive the shuttle;

Fig. 21 is a similar view, showing the two bights of thread after the shuttle horns have entered them;

105

Fig. 22 is a similar view, showing the po-

sition of the parts after the loop of the second stitch has been cast off by the shuttle, and just before the loop of the first stitch is cast off by the shuttle;

5 Fig. 23 is a fragmentary right side elevation showing the bights of thread drawn up through the materials by the needles held open by the spreader, ready for the passage therethrough of the shuttle;

10 Fig. 24 shows the position of the takeup and associated parts after the needles have drawn their bights of thread up through the materials;

15 Fig. 25 is an enlarged front sectional elevation of the work, work table or work support, and associated parts, showing diagrammatically the position of the thread after the looping operation is completed;

Fig. 26 is a plan of the loops; and

20 Fig. 27 illustrates diagrammatically seven steps in the formation of two stitches of a seam.

The invention is shown as embodied in a machine of the type of the Goodyear rapid 25 outsole stitcher, the general form and mode of operation of which are illustrated and described with substantial accuracy in the French and Meyer Patent No. 473,870.

Before entering upon a detailed description 30 of the various parts of the machine, it will be convenient first to refer to certain general features as a preliminary thereto. The main cam shaft S carries on its left-hand end the driving pulley, and on its 35 right-hand end is connected with the usual revolution counter. This main cam shaft S is supported in bearings at its opposite ends, and carries four cams, which are herein designated as the first, second, third and 40 fourth cams, beginning with the left-hand cam and counting to the right. These several cam disks may be referred to by the names of some of the conspicuous parts operated by them. Thus, the first cam 1 is 45 conveniently termed the take-up cam disk, the second cam 2 is called the shuttle or needle cam disk, the third cam 3 is called the awl cam disk, and the fourth cam 4 is called the feed cam disk.

50 A detailed description of the several stitch forming instrumentalities, their construction and mode of operation, will now be given, and then a description of the operation of the stitch forming instrumentalities in forming a seam will follow.

The needles N are two in number, and are located side by side a stitch length apart, and are carried by the needle segment 10 in the usual manner, pivoted in the frame of 60 the machine, and actuated by the needle lever 11 pivoted on the lever shaft 12 and carrying a cam roll which engages a cam path 13 in the right side of the cam disk 2 (Figs. 1 and 14). The needle guide 14 (Fig. 23) is provided with two holes to receive the two nee- 65

dles, and it has a segment 15 which is engaged by the pinion 16 mounted on the shaft 17, and which carries upon its left-hand end a segmental pinion 18 (Fig. 8) driven by the segmental gear 19 pivoted at 20 on the frame 70 of the machine, being actuated by an arm 21 carrying a cam roll 22 which engages a cam path 23 (Fig. 5), being the inner cam path, that is, the one nearer the shaft in the right-hand side of the cam disk 1. By 75 reference to Fig. 23, it will be observed that the two needles are of different lengths. Of these the left-hand needle, viewed facing the machine, is the longer, and the right-hand one is the shorter. This is for convenience 80 in looping. The needle cam path 13 is so shaped as to cause the needles to descend and enter and pass through the work, receive the thread in their barbs, and to withdraw, pulling two loops or bights of thread 85 through the materials. From an examination of the cam path of Fig. 14, it will be observed that the needles are held stationary 90 in their upper position for nearly one-half the revolution of the main shaft, that they descend quickly, and are then dipped slightly to facilitate the operation of the looper, and then withdrawn from the material to their retracted position and advanced slightly therefrom to disengage 95 themselves from the loops of thread drawn up by them, after which they move rearwardly again and then stand fast until they are again operated as before. The needle guide performs its usual function of supporting the needles. 100

The first needle, that is, the left-hand needle, as viewed in Fig. 3, is subjected to a lateral strain during the looping operation, as will hereinafter appear, owing to the pull of the thread thereon. At this time it is supported against lateral strain by a needle support 30 which is mounted on the end of the needle-supporting lever 31 (Fig. 4), pivoted at 32, carrying upon its rear end a pin 33 (Fig. 8), adapted to engage the side of the cam 34 mounted upon and projecting from the periphery of the cam disk 1. This needle support 30 carries a thread guard 35 near its needle-supporting end, which prevents the thread from becoming entangled with the needle support and other parts. 115

The two awls A (Fig. 19) are carried by the awl segment 40 (Fig. 4), pivoted at 41 on the feed slide in the usual manner. The 120 awl segment 40 is actuated by the awl segment lever 42 (Fig. 7) pivoted at its rear end upon the lever shaft 12 and bearing a cam roll 43 which is received in the awl cam path 44 of the cam on the left side of the 125 cam disk 3. The shape of the awl cam path is such as to cause the awls to be forced up into and through the material or stock M to be sewed, after which their retraction begins, but they remain in engagement with 130

the material during the time they are moving laterally to feed the work, after which, and as the needles descend, their retraction is completed. The awl segment is mounted 5 upon the feed slide F (Fig. 7), which is mounted in the usual guides and actuated by the feed lever 50 (Fig. 8) pivoted at 51 upon a stationary part of the machine, carrying 10 upon its front end a groove which receives the pin 52 attached to the feed regulating lever 53, and carrying upon its rear end a cam roll 54 which engages a feed cam path 55 in the feed cam disk 4 (Fig. 18). The throw of this cam is such as to reciprocate 15 the feed slide the length of two stitches, or double the distance between the awls and between the needles.

It is to be observed that the distance between two stitches simultaneously made by 20 the two needles is fixed and constant, and that the distance between this pair of needle holes and the next pair of needle holes may be varied by adjustment of the feed regulating lever. While it is preferred to have 25 the feed of such a length as to make the distance between the last hole of one pair of needle holes and the first hole of the next pair of needle holes the same as the distance between the needle holes of each pair, it is 30 not a matter of substantial consequence if every other stitch depart slightly from this length, as it would not constitute a detriment to the finished work. Thus, in stitching outsoles, that portion of the seam extending around the forepart should preferably have all of the stitches of uniform 35 length, while along the shank the stitches might vary in length without prejudice to the acceptability of the work, because this 40 portion of the seam is not conspicuous, and in fact is rarely to be seen by the user of the shoe.

The looper L is mounted on the end of the looper lever 60 (Fig. 8), which is slidably 45 mounted in the looper carrier 61 pivotally supported at 62 upon a stationary part of the frame of the machine. The lateral position of the looper is determined by swinging the looper carrier 61 upon its pivot. This 50 swinging motion is imparted to the looper carrier by means of the lateral looper cam roll 63 mounted upon the forward portion 64 of the looper carrier 61, which lateral looper cam roll 63 engages the cam path 65 (Fig. 16) in the periphery of the cam disk 2. The forward and back movements of the looper are imparted by the looper bell crank lever 66, one arm of which engages a block pinned on the looper lever 60, and the other 55 60 arm of which carries the forward and back looper cam roll 67 which engages the cam path 68 (Fig. 17) in the periphery of the cam disk 3. These two levers operate to move the looper in a path to lay the thread 65 over the thread hooks and in the barbs of the

needles. At the end of the formation of a pair of stitches the looper stands with its eye 69 in line with the thread extending from the work to the take-up. The looper first moves from this position to the rear of 70 the thread hook 70 (Figs. 25 and 26), thence to the right behind the thread hook 71, and on to the right and in front of and beyond the first needle N, thence rearwardly and around the needle, laying the thread in the 75 barb thereof, thence to the left and in front of the thread hook 71, around behind it, and thence to the right in the rear of the first needle, then forward, and then on to the right (at which time the needles move downward), laying the thread in the barb of the second needle, thus forming two loops or bights of thread, the first of which is of sufficient size to permit the shuttle to pass through it and the second of which is of 80 sufficient size to see the needle through the work and to the extremity of its retracting stroke without reeving through the barb or hook of the needle. (The remainder of the thread necessary to enlarge this second loop 85 sufficiently to permit the shuttle to pass through it is drawn up by the shuttle itself.) The two thread hooks 70 and 71 are mounted upon stationary parts of the machine (see 90 Figs. 19 and 4) near and to the left of the 95 sewing point, the thread hook 71 being pivoted at 72 upon the left-hand end of the work support W, and the thread hook 70 being pivoted at 73 upon an arm 74 projected to the left from the left-hand end of the 100 work support W. The thread hook 7 is locked in operative position, as shown in Fig. 19, by means of the thread hook lock 75 (see also Fig. 4) which is formed upon the forward end of a lever 76 pivoted at 32 105 (Figs. 4 and 8), which lever carries on its rear end a cam roll 77 adapted to engage the cam path 78 in the periphery of the cam disk 1. During the time the needle is looping the thread around the thread hooks and 110 barbs of the needles, the thread hook lock 75 occupies the position shown in Figs. 4, 8 and 19, engaging the upwardly projecting portion 80 of the thread hook carrier 81 so as thereby to prevent the thread hook 70 from 115 being turned upon its pivot by the tension of the thread thereon. The link 82 connects the thread hook 70 and the thread hook 71, and when the thread hook 70 is held from movement, the thread hook 71 is likewise held. 120 A spring 83 attached to the upper part of the thread hook carrier 81 normally holds the thread hooks in the position shown in Fig. 19 with yielding force so that when the thread hook lock is moved away from the 125 thread hook carrier 80 and sufficient tension is exerted upon the thread, the thread hooks 70 and 71 will turn and thereby disengage themselves from the loops of thread held thereby. The thread hook 70 is secured to 130

the thread hook carrier 81 by a screw 84 (Fig. 25), the carrier being slotted so as thereby to permit adjustment of the position of thread hook 70 to secure the proper length 5 of loop held by it.

The work support, or work table, W, above referred to in connection with the thread hooks 70 and 71, occupies the conventional position for supporting the work, 10 having a flat top provided with a long slot to receive the awls and to permit their feeding movement to feed them into position opposite the needles. It also has a depending apron or front which protects the shoe 15 upper from contacting with the awls, looper and needles. It is provided in its front side with a hole 90 located between the needle positions to receive a lower thread retainer 91 (Figs. 4, 19, 23 and 25). This 20 thread retainer 91 is supported in a hole in a stationary part of the machine, specifically the needle segment support. This lower thread retainer 91 has a shank which is cylindrical in form; its operative end is 25 rectangular and somewhat thinner than the distance between the needles; it is actuated by a lever 92 (Figs. 4, 8 and 9) arranged below the work support and pivoted at 93 on a stationary part of the machine. The 30 other end of the lever 92 is slotted at 94 and in the slot is received a pin 95 supported in the thread hook lock lever 76. The lower side of the shank of the lower thread retainer 91 is transversely slotted to 35 receive the end of the lower thread retainer operating lever 92. The arrangement is such that when the forward end of the thread hook lock lever moves to the right it causes the lower thread retainer operating lever 92 to be swung so as to retract or 40 move back the lower thread retainer, and vice versa. Thus, when the needles are being looped, at which time the thread hooks are held fixed, the lower thread retainer is 45 in retracted position, but as soon as the thread hooks are released the lower thread retainer is moved forward into position between the needles so that as the needles draw up their two bights of thread, the thread 50 extending from the first needle hole to the second needle hole is bent around the lower thread retainer. Thus, with the parts in the position shown in Fig. 19, the lower thread retainer 91 is in retracted position, while, 55 when the parts are in the positions illustrated in Fig. 20 the lower thread retainer has been forced forward and engages the thread between the stitch holes during the time the shuttle is passing through the loops 60 drawn up by the needles.

The tension wheel T mounted on a stationary part of the machine receives the thread 100 coming from the wax pot, which thread passes entirely around the tension 65 wheel and thence around a thread truck 101

from which it passes on to the thread measurer 102. After passing over the thread truck on the thread measurer, the thread passes down around the thread truck 103, thence up over one of the thread trucks 104 70 of the auxiliary take-up or slack thread controller 105 from which it passes to one of the thread trucks 106 on the take-up 110, from which it passes around the other thread truck 104 of the auxiliary take-up and 75 thence down around the other thread truck 106 of the take-up 110, from which it passes through the thread eye 111 to the eye 69 of the looper L. It will be noted that there are two thread trucks 104 and two thread trucks 106. This is because of the large amount of thread necessary to be handled owing to the passing of two loops over the shuttle at each cycle of operations. 80

The thread trucks 101 and 103 are both of them thread lock trucks, the thread lock 112 being arranged between the two thread trucks 101 and 103 and adapted to engage the thread on either the one or the other, or neither, as the case may be. This thread lock 112 is pivotally mounted on the pivot 113 and provided with a rearward extension 114 which is received in a notch 115 in the disk 116 mounted on the rock shaft 117. To this rock shaft 117 is attached an arm 120 85 which is connected by means of the link 121 with the bell crank lever 122 pivoted at 123 on a stationary part of the machine, which bell crank lever 123 carries upon its end a cam roll 124 which engages the outer cam path 125 in the right-hand side of the cam disk 1 (Fig. 5). The throws of this cam path are such that the thread is locked against being pulled from the tension while the looper is looping the needles and thread 90 hooks, thus preventing thread from being stolen from the tension during such operation, and, again, during the time the stitches are being set, at which time, of course, it is necessary that the thread be locked, owing to 95 the strain exerted thereon, to prevent it from being drawn from the tension, and also during the time the thread measurer or pull-off is acting. During the first part of the looping operation, and during the pull-off operation, the thread is locked against the thread truck 103, and during the latter part of the looping operation the thread is locked 100 against the thread truck 101. 110

The thread measurer or pull-off 102 is 115 mounted on the rock shaft 130 supported in a stationary part of the machine which shaft carries upon its right-hand end an arm 131 which is actuated to oscillate the shaft 130 through the mechanism constructed and organized substantially as in said patented machine, except that owing to the increased amount of thread necessary to be pulled off from the tension by the thread measurer, due 120 to the requirement that the thread for the 130

formation of two stitches is pulled off at each cycle of operations, the amplitude of oscillation of the thread measurer is increased, as a consequence of which the harp 5 132 is widened to accommodate the larger throw of the link 133 connected with the bell crank lever 134. Provision is also made for adjustment of the position of attachment of the link 133 to the depending arm 10 of the bell crank lever 134 to accommodate the thread measurer to different qualities of stock and different tightnesses of seam. The forwardly extended arm of the bell crank lever 134 carries upon its end the cam 15 roll 135 (Fig. 2), which engages the cam path 136 (Fig. 13) on the left-hand side of the cam disk 4.

The take-up arm 110 (Fig. 6) is provided with a cam 140, the operating surface 141 of 20 which is adapted to engage the pin 142 of the spring-controlled auxiliary take-up lock 143. This auxiliary take-up lock 143 consists of a lever pivoted at 144 on a stationary part of the machine. It has a hook at 25 its end which engages a hook 145 on the lower side of the auxiliary take-up. At times when the cam surface 141 is in engagement with the pin 142, the hook is prevented from engaging the hook 145. The 30 auxiliary take-up lock 143 is a two-part affair consisting of a lever 146 to which is secured the part 147 provided with the slot 148 to receive the screw 149 by which the two parts are adjustably connected. This 35 holds the auxiliary take-up from action during the first part of the looping operation, that is, during the time the looper is moving from its position near the sewing point out around the thread hook 70 and about half 40 way back to the first needle, but it is released for subsequent operations.

The take-up 110, pivoted at 113, has an arm 160 connected by a link 161 with a take-up cam lever 162 pivoted at 163 on a 45 stationary part of the machine and provided on its upper end with a cam roll which engages the cam path 164 in the left side of the cam disk 1. The take-up is operated by this mechanism to give up thread to the looper 50 during the looping operation, to pull back or take up the needle loops and to tighten and set the first stitch in a manner more particularly hereinafter described in connection with the description of the operation 55 of the machine.

The shuttle, or loop taker, S' oscillates on a horizontal axis and in a vertical plane at the front of the machine. It is supported in a shuttle race 170. The shuttle has a 60 horn 171 and a bobbin case 172 which receives the spool of shuttle thread 173. The bobbin case is held in place by the screw 174. The shuttle thread tension is secured by leading the shuttle thread out through 65 the hole 175 in the side of the bobbin case,

thence over the hinge of the shuttle tension and thread locking device 176, pivoted at 177 to the periphery of the bobbin case, thence back through the hole 178 under the hinged shuttle tension and thread locking 70 device 176, thence along between the device and the bobbin case, out through the hole 179, along the outer surface of this locking device 176, back under it again through the hole 180, and thence radially inward under 75 the shuttle take-up member 181 (Fig. 19) and out through the hole 182 thereof, whence the thread leads to the work. This shuttle take-up device 181, shown in cross section in Fig. 10, is held in place by the shuttle take-up locking screw 183. By moving the take-up 80 181 to the right or the left, as shown in Fig. 19, the distance of the hole 182 from the center of the shuttle may be increased or diminished so as thereby to increase or 85 diminish its eccentricity with relation thereto, to increase and diminish the amount of shuttle thread taken up in setting the second stitch. It is convenient here to remark that, as already pointed out, the first stitch 90 is set by the take-up and the second stitch is set by the shuttle, the thread lock being pulled down into the material by the take-up so that the thread lock of the first stitch is near the top of the work and the thread 95 lock of the second stitch is pulled up into the material by the shuttle leaving the lock near the lower surface of the work. The shuttle is provided with a shuttle thread clamping pin 190 (Figs. 9 and 19) which 100 is received in a hole in the shuttle and engages with its inner end the outside of the shuttle thread tension device 176, and engages with its other end the ball 191 which normally projects slightly beyond the surface of the shuttle and is adapted to engage the cam surface 192 on the shuttle race during the setting of the stitch by the shuttle. The bobbin case 172 is provided with a flange 193 which engages a corresponding flange 110 on the shuttle (see Fig. 10), being held thereagainst by the screw 174 above referred to. The shuttle is cut away for a considerable portion of its periphery, as shown in Fig. 9, and the shuttle race is likewise cut 115 away for a long distance, this being required by the necessity for the shuttle's handling two loops of the lower or needle thread. In order to sustain the shuttle efficiently in a concentric position in the shuttle race so as 120 to be capable of being oscillated without cramping, the shuttle is provided upon its periphery with a laterally projected flange 194 which, with the outer wall of the shuttle, forms a groove that receives the flange 195 of the shuttle retainer 196 secured to the shuttle race by the screws 197. The shuttle is actuated by the shuttle driver 200 which 125 consists of a disk 201 on the end of a shuttle driving shaft received in the shuttle race 130

and provided with two arms 202 and 203, the former of which is received behind the horn of the shuttle, and the latter of which engages the shuttle near the end of its cutaway portion. The space between these two arms is provided, of course, to receive the needle segment. They are united by a little bridge 204 which is provided to prevent the thread from accidentally catching upon the 5 corners of these arms. The rear end of the shuttle driving shaft carries a bevel pinion 205 which is engaged by a segmental bevel gear 206 (Fig. 1) pivoted on the lever shaft 12 and bearing a stud carrying a cam roll 207 which engages the cam path 208 in the 10 left side of the cam disk 2. The shuttle driver 201 has a smooth front face so that nothing shall engage either of the loops of the thread passing between the shuttle and 15 it while the shuttle is passing through the loops drawn up by the needles. The arm 202 of the shuttle driver is provided with a spring horn 210 which normally occupies a position alongside of and slightly within 20 the point of the horn 171 of the shuttle, as shown in Fig. 19. This spring horn is provided with a shank which is received in a hole in the shuttle arm 202 and is encircled by a torsion spring fastened at its front end 25 to the shuttle arm 202 and at its rear end to the disk 211. This disk 211 has a shoulder which takes against a stop 212, the disk being pinned to the shank of the horn 210. When inserted in the shuttle the spring is 30 put under tension so that it normally tends to turn the spring horn outward close to but within the shuttle horn 171. The shuttle horn 171 enters both of the loops of thread drawn up by the needle but the shuttle 35 driver horn 210 enters only the loop drawn up by the first needle. When the shuttle has turned to the position where it casts off the loops through which it is passing, the shuttle driver horn 210 casts off its loop after 40 the other loop has been cast off by its turning movement, under the influence of the pull exerted by the loop upon it against the action of this torsion spring. The description of the operation of the shuttle 45 horn and shuttle driver horn will be elaborated in connection with the description of the operation of the machine.

The spreader or thread lifter 220 (Fig. 20) is provided with two hooks 221 and 222 50 adapted to engage, respectively, the loops drawn up by the first and second needles. The spreader 220 has a shank 223 which is secured in the front end of the spreader arm 224 (Fig. 23) pivoted at 225 on a stationary part of the machine. This spreader arm 224 has attached to it a rearwardly extended arm 226, which supports a pin carrying pivotally mounted thereon a block 55 which is received in the jaw 227 at the front end of a lever 228 pivoted at its rear

end upon the lever shaft 12 and bearing upon its side a stud carrying a cam roll 229 which is received in the cam path 230, being the inner cam path on the right side of the cam disk 3. When the needles are in 70 their lowermost position the spreader is down (see Fig. 19) and the needles first draw up their two loops of thread, laying the outer sides of the bights or loops of thread on the spreader hooks 221 and 222. The hooks do not extend toward each other beyond the adjacent sides of the needles, so it is that the two sides of the loops of thread drawn up by the needles lying adjacent to each other are not caught by the 75 spreader hooks. After the needles have retracted sufficiently to clear the spreader, the spreader rises to the position shown in Fig. 20, and the loops are thereby opened, as shown in Fig. 23, ready for the entrance 80 of the shuttle. 85

After the loops have been drawn up by the needles, and before the shuttle enters the loops, an upper thread retainer or loop separator 240 (Fig. 4) enters the space between the two loops of thread and separates the loops. This upper thread retainer or loop separator consists of a pin mounted on the end of the lever 241 pivoted at 242 on a part of the feed slide or awl carrier. 90 The rear end of this lever 241 is connected by means of a link 243 with a lever 244 (Fig. 8) pivoted at 51 on a stationary part of the machine. The rear end of the lever 244 carries a cam roll 245 which engages the 95 laterally acting cam 246 (Figs. 1, 3, 13 and 18) on the right side of the cam disk 4. This upper thread retainer or loop separator is operated to enter the space between the two loops and to separate the two loops during the time the shuttle is passing through them, and it remains there until the take-up has pulled back upon the second loop of thread and pulled the shuttle thread down through the work. It 100 thereby acts to provide a slackness in the shuttle thread between the last completed stitch and the second stitch which provides thread so as to sink the lock of the first stitch into the material when the first stitch comes to be set upon the continued movement of the take-up. It will 105 be observed that this cam 246 holds the upper thread retainer or loop separator retracted for the greater part of a cam shaft revolution, so that for a short time only is the loop retainer held between the two loops for the purpose of separating them and providing sufficient slack thread in the upper or shuttle thread to sink the lock into the 110 materials. 115

After the setting of the first stitch by the take-up (which occurs after the upper thread retainer has been withdrawn) the abutment 250 (Fig. 4) is moved into the position illus. 120 125 130

trated in Figs. 4 and 8, and it then engages the left-hand side of the shuttle thread running from the second needle hole to the shuttle and affords a support over which the 5 shuttle thread may reeve during the setting of the second stitch by the shuttle. This abutment 250 is carried on the left-hand end of the lever 251 pivoted at 242 upon the feed slide or awl carrier. The link 253 10 connects the rear end of the lever 251 with the front end of the lever 254 pivoted at 51, and carrying upon its rear end a cam roll 255 which engages the laterally acting cam surface 256 on the left side of the cam 15 disk 4.

The work clamp 260 (Figs. 4 and 7) is operated in the same general way as in the machine of said patent. It is mounted on the front end of a lever 261 pivoted at 262, 20 carrying on its rear end the harp 132 which coöperates with the thread measurer. To the work clamp or presser foot lever 261 is attached a spring rod 263 which is actuated by the arm 264 as in said patent, the 25 latter arm 264 being lifted in timed coöperation with the other instrumentalities of the machine to cause the work clamp or presser foot to clamp and hold the material by means of work clamp or presser 30 foot actuating lever 265 which carries at its front end a pawl 266 which engages a ratchet 267 on the rear end of the arm 264. This lever 265 is pivoted at 268 on a stationary part of the machine, and carries upon its side a cam roll 269 which 35 engages a cam path 270, being the outer cam path in the right side of the cam disk 3. The clamp releasing lever 280 is also pivoted at 262, and it carries upon its lower 40 end the pawl pusher 281 which has two arms, one arm 282 which engages the pawl 266 to lift it, and the other arm 283 which engages the pawl 284, which engages the ratchet 285 on the rear end of the work 45 clamp lever 261.

Coming now to a description of the operation of the stitch-forming instrumentalities in forming a seam of stitches, reference will be made more especially to Figs. 19, 20, 21, 50 22, 23, 24, 25 and 26, which show the parts in different positions during the formation of a pair of stitches of a seam, and to Fig. 27 which shows the thread in different positions during one cycle of operations of the 55 machine. By reference to Figs. 25 and 27 it will be seen that the lock of the stitches is located alternately near the top of the material, as it is positioned in the machine, and near the bottom of the material, the 60 lock of the first stitch being near the top and the lock of the second stitch being near the bottom.

After the awls have risen through the materials and formed two punctures therein 65 to receive the needles, and the feed has taken

place, the needles descend through the awl holes in the materials and occupy the positions illustrated in Fig. 25. The looper L moves to the left and the thread from the last preceding stitch is bent around the 70 needle support 30 and laid over the thread hook 70. In making this movement the looper, beginning its movement before the awls begin their puncturing movement, passes from the position shown in Fig. 27, 75 position 1, to the left, behind the needle hook 71, on behind and beyond the needle hook 70, thence forward, and then to the right behind the needle hook 71, the needles having descended through the materials by 80 this time, thence in front of the left-hand needle end, then rearwardly, and then to the left, thereby laying the thread in the barb of the left-hand needle, thence it continues its movement to the left passing in 85 front of the needle hook 71, then rearwardly and to the right back of the left-hand needle end to a position between the two needles, then the looper moves forward and the needles descend slightly, then the looper 90 moves to the right and rearwardly, thereby laying the loop in the barb of the hook of the second needle, and the thread occupies the position illustrated in elevation in Fig. 25 and in plan in Fig. 26. The strain exerted by the thread upon the first needle would tend to pull it to the left. This strain is resisted by the needle support 30 which engages the side of the first needle as soon as it has descended through the materials 100 and just as the looper lays its thread in the barb thereof. By an examination of Fig. 25, it will be observed that the longer loop or bight 300, that is, the loop or bight held by the left-hand needle and the thread hook 105 70, is of sufficient length to see the needle back and to pass over the shuttle without reeveing of the thread in the barb of the needle or around the material between the first needle and the second needle. The 110 second loop 310 is much shorter, and is sufficient to supply thread for the left side of the thread loop drawn back by the second needle, that is, sufficient to see the needle back to the extreme of its throw without 115 reeveing in the barb thereof, but it is not intended to be sufficient to pass the thread over the shuttle, as it merely supplies thread for approximately one-half of the length required for that purpose, the other half of 120 the thread for this loop or bight 310 being drawn by the needle or shuttle, or both, from below the work. By reference to Fig. 19, it will be seen that the take-up at this time 125 is not completely raised during the formation of the second loop 310 of thread. After this, the needles rise, and the take-up also rises, and the parts assume the position illustrated in Figs. 20 and 23, that is, after the needles have partially risen, the spreader 130

or thread lifter 220 rises and lifts the outer sides of the needle loops and distends these loops to the positions shown in Fig. 23, so as to occupy the position to receive the 5 shuttle therethrough. The shuttle horn 171 and the shuttle arm horn 210 enter the needle loops, the shuttle horn 171 entering both loops and the shuttle arm horn 210 entering the left-hand loop only. This is 10 for the purpose of concatenating or enchain- 15 ing the shuttle thread with the loops of the needle or lower thread, the shuttle arm horn 210 taking the loop 300 separates it from the loop 310, so that the latter may be cast off from the shuttle before the former, this being necessitated by the operation of pulling back the second loop first. In this connection, it will be observed that the two hooks 221 and 222 of the spreader or thread 20 lifter 220 occupy slightly different planes, as seen in Fig. 23, which coöperate with the long and short needles N to separate the two loops, so as to permit the spreader arm horn 210 to enter the loop 300 without entering the loop 310. The hook 221 is farther forward than the hook 222, as shown. Furthermore, it should be mentioned that at the time the needles start upward, the lower thread retainer 91 is thrust forward between 25 the two needles, so that the thread extending on the lower side of the work from the first needle hole to the second needle hole is drawn up against this lower thread retainer and retained thereby to afford the thread 30 to sink the lock of the second stitch in the material in the second needle hole, as hereinafter described in connection with the setting of the second stitch. After the shuttle has entered the loops, the parts assume the 35 position indicated in Fig. 21. Then the shuttle, continuing its movement, casts off the second loop 310 from the shuttle in the usual manner, the take-up pulling back upon the needle thread, the thread being locked 40 against the thread truck 101 at this time, to prevent pulling off thread from the tension during such take-up operation. Before the taking up of this second loop 310 occurs, the upper thread retainer 240 is 45 thrust between the two loops 300 and 310, and then as the second loop 310 is cast off and pulled back through the materials, it pulls back with it the shuttle thread, as shown in Fig. 22, the upper thread retainer 50 240 retaining sufficient shuttle thread between the last completed stitch, and the second stitch being formed, to allow the setting of the lock of the first stitch down into the materials. A loop of the shuttle thread is 55 thus drawn down entirely through the work, as shown diagrammatically in position 5 of Fig. 27, and thereupon the first loop 300 is drawn back by the take-up and the upper thread retainer 240 is withdrawn from under 60 the shuttle thread, and the needle thread

engaging the slack shuttle thread above the material, pulls the lock down into the material, as shown in position 6 of Fig. 27, thereby setting the first stitch in the material, as shown. Now the lower loop retainer 70 91 is withdrawn from under the work and the shuttle, on its backward movement, takes up the loop of shuttle thread drawn down through the materials, and pulls the lower or needle thread into the materials and sets 75 the second stitch. In order to prevent the displacement of the threads in the second needle hole during this shuttle take-up operation, the abutment 250 is laid alongside of the shuttle thread, as shown in positions 80 6 and 7, thus forming a support over which the shuttle thread reeves in setting the stitch. In Fig. 22 the pulling of the shuttle thread down into and through the materials by the loop 310 has not quite been completed, but as soon as it is completed, the shuttle arm hole horn 210 yields, under the tension of the thread, and moves from the position shown in full lines to the position 85 shown in dotted lines, and thereby casting 90 off the loop 300. Fig. 24 shows the take-up at its upper extremity of movement at the time when both loops of thread 300 and 310 have been completely formed to their full size, and therefore at the time when the 95 take-up is at the top of its stroke and when the auxiliary take-up is unlocked and free to take up any slack which may occur in the lower or needle thread.

Fig. 27 illustrates diagrammatically the 100 successive operations of forming a pair of stitches. Thus, position 1 illustrates dia- 105 grammatically a portion of the seam being formed. Position 2 shows the two needles thrust down through the materials, the left one being supported by the needle support, the loops of thread having been formed upon the under side of the work and the thread having been laid in the hooks of the needles and the lower loop retainer 110 91 having been thrust forward into position to engage the thread between the two needle holes when the needles rise. Position 3 shows the two loops of thread drawn up by the two needles with the lower 115 loop retainer 91 holding the thread between the two needle holes and the upper thread retainer 240 in position against the work between the two loops of thread ready to have the shuttle thread drawn against it. 120 Position 4 shows the parts after the shuttle thread has been passed through both loops of needle thread. Position 5 shows the position of the thread after the loop 310 has been taken up, thereby pulling the shuttle 125 thread down through the second needle hole and against the upper thread retainer 240. Position 6 indicates that the upper thread retainer 240 has been removed and the continued action of the take-up has taken up or 130

pulled back the entire loop 300, thereby sinking the shuttle thread into the material in the first needle hole and setting the first stitch by the action of the take-up. At this time the abutment 250 is brought into position against the shuttle thread ready to support it at the next operation. In position 7 the shuttle thread has been pulled up by the shuttle, being supported by the abutment 250, and pulled the lower or needle thread into the second stitch hole and set the lock of the thread in the materials above and near the lower surface thereof.

It is to be observed that the machine of this application may be modified in various respects without departure from the invention. Thus, the lower thread retainer and shuttle thread lock may be omitted, in which case the first stitch is set by the take-up, as indicated in position 6 of Fig. 27, there being, however, no lower thread retainer 91 nor any shuttle thread lock, the loop of shuttle thread drawn through the second needle hole is not as long as shown in position 6, but extends approximately to the lower surface of the materials only. The second stitch, therefore, is not set by the shuttle, as in the preferred embodiment, but is either not set at all, being simply tautly positioned against the material, or it is set during the formation of the next two stitches when the first stitch of the next pair is set, in a manner familiar to those skilled in this art by the stealing of thread from the old stitch during the setting of the first stitch of the next pair of stitches.

While this invention is particularly intended and is believed to be more especially useful in wax thread leather sewing machines, such as the curved needle outsole stitcher in which it is shown as embodied in the drawings, or in other forms of wax thread sewing machines, still it is to be understood that the invention is not limited to wax thread leather sewing machines, as it may be employed to advantage in other forms of machines. The invention, viewed in its broader aspects, is not limited to use in connection with two needles, as a larger number of needles may be employed.

Having thus described the invention, what is claimed is:—

1. A sewing machine having, in combination, stitch forming devices including a plurality of needles for passing a plurality of loops of the same thread through the work, a loop taker for coöperating with said plurality of loops, and means for actuating said devices to form a plurality of stitches in a single seam at a single cycle of operations and to form a continuous seam during a plurality of cycles of operations.

2. A sewing machine having, in combination, stitch forming devices including a plurality of needles for passing a plurality of

loops of the same thread through the work, a shuttle for coöperating with said plurality of loops, and means for actuating said devices to form a plurality of stitches in a single seam at a single cycle of operations. 70

3. A sewing machine having, in combination, stitch forming devices including a plurality of needles for passing a plurality of loops of the same thread through the work, a loop taker for coöperating with said plurality of loops, a stitch setting take-up mechanism, and means for actuating said devices to form a plurality of stitches in a single seam at a single cycle of operations and to form a continuous seam during a plurality of cycles of operations. 80

4. A sewing machine having, in combination, stitch forming devices including a plurality of needles for passing a plurality of loops of the same thread through the work, a shuttle for coöperating with said plurality of loops, a stitch-setting take-up mechanism, and means for actuating said devices to form a plurality of stitches in a single seam at a single cycle of operations. 85

5. A lock-stitch sewing machine having, in combination, stitch forming devices including a loop taker, a plurality of needles, loop forming devices acting to form loops in the needle thread on one side of the work 95 corresponding in number to the needles, and means for actuating the parts to cause the needles to pass the loops through the work to the opposite side, and the loop taker thereafter to pass the locking thread 100 through the loops.

6. A lock-stitch sewing machine having, in combination, stitch forming devices including a shuttle, two needles, loop forming devices acting to form loops in a single 105 thread on one side of the work, and means for actuating the parts to cause the needles to pass the loops through the work and to pass the shuttle through the loops.

7. A sewing machine having, in combination, a loop-taker, a plurality of needles co-operating with the loop taker to form a plurality of stitches during a single cycle of operations of the machine, and stitch-setting devices acting to successively set the stitches 110 formed by the loop taker and needles. 115

8. A lock-stitch sewing machine having, in combination, a shuttle, two needles for passing two loops of a single thread through the work, needle actuating means, a 120 stitch-setting take-up and means for actuating said shuttle and take-up to draw tight said two loops of thread to form two stitches in a single seam during a single cycle of operations of the machine. 125

9. A lockstitch sewing machine for forming a two-thread lockstitch seam, having, in combination, means for pulling two loops of one thread through the materials, means for passing the other thread through such 130

loops, and means for setting the stitches, all operating during a single cycle of operations of the machine.

10. A two-thread lockstitch sewing machine having, in combination, means for passing two loops of one thread through the materials and passing the other thread through such loops, stitch-setting devices having provision for setting the first stitch 10 by a pull on the looped thread and for setting the second stitch by a pull on the other thread.

11. A two-thread lockstitch sewing machine having, in combination, a shuttle, devices for passing two loops of thread through the materials, devices for passing the shuttle through the two loops, an upper loop retainer, a lower loop retainer, means for setting the first stitch by a pull on the 15 looped thread, and said shuttle having provision for setting the second stitch by exerting a pull on the shuttle thread.

12. A lockstitch sewing machine employing an upper and lower thread and having, 25 in combination, a shuttle, means to pass two loops of thread through the materials to form two stitches, an upper thread retainer, and means coöperating therewith for setting the first stitch by a pull on the loop of 30 thread.

13. A lockstitch sewing machine having, in combination, a shuttle, a hooked needle, a looper for looping the needle, and a needle support on the looper side of the work for 35 supporting the needle against the lateral strain of the thread due to looping.

14. A lockstitch sewing machine having, in combination, a shuttle, two needles, a looper for forming two loops and looping 40 the needles, and means for passing the shuttle through the loops drawn through the material by the needles.

15. A lockstitch sewing machine having, in combination, a shuttle, two needles, a 45 needle support for supporting one of the needles, a looper for forming loops in the thread and looping the needles, two thread hooks each for holding one of the loops of thread, a lower thread retainer for providing 50 thread to see the lock of the second stitch into the materials, and an upper thread retainer for providing thread to see the lock of the first stitch into the material.

16. A lock-stitch sewing machine having, 55 in combination stitch forming devices including a needle and coöperative instrumentalities for forming a lock stitch seam, a shuttle, means for actuating the shuttle to set the stitch, and an abutment for engaging the shuttle thread during the stitch setting operation.

17. A lock-stitch sewing machine having, 60 in combination, stitch forming instrumentalities, two needles, a spreader or thread

lifter coöperating with both needles, an upper thread retainer, a shuttle, means for actuating the shuttle to set a stitch, and an abutment for supporting the shuttle thread during the setting of the stitch. 65

18. A lock-stitch sewing machine having, 70 in combination, stitch forming instrumentalities for forming two stitches, including two needles, a spreader coöperating with both needles, an upper thread retainer, a shuttle, means for actuating the shuttle to 75 set one of the stitches, a lower thread retainer, a looper, means for actuating the looper to form two loops in a single thread to loop both needles, and a needle support to support a needle against the strain of loop- 80 ing the thread.

19. A two-thread lock-stitch sewing machine having, in combination, stitch forming instrumentalities for forming two stitches at a single operation, including means for 85 passing two loops of thread through the work, a shuttle coöperating with both loops, an upper thread retainer, means coöperating with the upper thread retainer and pulling on the lower thread to set the first stitch, 90 means for actuating said shuttle to set the second stitch and a lower thread retainer coöperating with said shuttle.

20. A lock-stitch sewing machine having, 95 in combination, stitch forming devices including means for passing two loops of thread through the material to form two stitches at a single operation, a shuttle coöperating with both loops, a take-up mechanism, means for actuating said take-up to 100 set one of the stitches, and means for actuating said shuttle to set the other of said stitches.

21. A lock-stitch sewing machine having, 105 in combination, stitch forming devices including two needles for passing two loops of a single thread through the work to form two stitches of a single seam at one operation, a shuttle coöperating with both loops, a take-up mechanism, means for actuating said take-up to 110 set the first stitch, and means for actuating the shuttle to set the second stitch.

22. A sewing machine having, in combination, stitch forming devices including two 115 needles and coöperating instrumentalities for forming two stitches in a single seam at a single cycle of operation of the machine, a feed slide, and means for reciprocating the feed slide through a distance equal to 120 the length of two stitches at each cycle of operations.

23. A sewing machine having, in combination, stitch forming devices including two needles and two awls for forming two 125 stitches in a single seam at a single cycle of operations, said needles and awls being a fixed distance apart, whereby the length of

one stitch is fixed, a feed slide and adjustable means for reciprocating the feed slide through varying distances whereby the length of the other stitch may be varied.

- 5 24. A lock-stitch sewing machine having, in combination, stitch forming devices including two needles for passing two loops of thread through the work to form two stitches at a single cycle of operations, a 10 shuttle having a horn formed thereon, a shuttle driver for passing the shuttle horn through both loops of thread, and an auxiliary horn on said shuttle driver to engage one of the loops.
- 15 25. A sewing machine having, in combination, stitch forming devices including a plurality of needles and coöperating instrumentalities for forming a plurality of stitches in a single seam at a single cycle 20 of operation of the machine, and means for feeding the work to space the groups of stitches made during successive cycles.
- 25 26. A lock-stitch sewing machine having, in combination, stitch forming devices including two needles for passing two loops of thread through the work, a loop taker for passing a locking thread through said loops, and means for holding the loops sep-

arated during the passage of the locking thread therethrough. 30

27. A lock-stitch sewing machine having, in combination, stitch forming devices including two needles for passing two loops of thread through the work, a loop taker for passing a locking thread through said loops, and means for holding the loop separated during the passage of the locking thread therethrough, and for causing the loops to be cast from the loop taker successively. 35

28. A sewing machine having, in combination, devices for passing loops of thread through the work and a locking thread through the loops to form the stitches of a lock-stitch seam, and means for setting 40 the stitches with the locks alternately nearer opposite sides of the work.

29. A sewing machine having, in combination, devices for passing loops of thread through the work and a locking thread 45 through the loops to form the stitches of a lock-stitch seam, and means for setting the stitches with certain of the locks nearer one surface of the work and other locks nearer the other surface of the work. 50

MICHAEL F. BROGAN.
